Application September 14, 1944, Serial No. 554,122

2 Claims. (Cl. 178—7.1)

1

This invention relates to an electronic control means responsive to variations in light intensity for operating a control mechanism, and particularly to means for automatically adjusting the size of the lens aperture for television apparatus.

The invention comprehends an electronic control means responsive to variations in light waves for automatically operating desired apparatus in response to said variations for controlling said light waves or other desired means.

The invention further comprehends the provision of means for automatically setting the iris of an optical system and adjusting its setting during changes in scene brightness for maintaining a substantially constant illumination level at an image position of said system receiving light from a scene through the iris aperture.

The invention provides means responsive to variations in amplitude of the video signal resulting from variations in scene brightness for automatically adjusting the iris to open and close the opening in the iris for maintaining substantially constant illumination of the photo-sensitive surface or mosaic in the pick-up tube.

The invention further comprehends the provision of means for initially setting the opening in the iris in combination with means responsive to variations in the video signal resulting from variations in scene brightness for automatically adjusting the setting of the iris for either opening or closing the opening therein as scene brightness either decreases or increases from the initial brightness to thereby obtain a substantially constant level of illumination of the photo-sensitive surface or mosaic in the pick-up tube.

The invention comprehends the provision of an automatic iris adjusting and control mechanism arranged so that the iris may be set initially or at any subsequent time through the operation of manually controlled means for obtaining a desired degree of illumination of the mosaic in the pick-up tube with means responsive to variations in amplitude of the video signal for thereafter adjusting the iris automatically with variations in scene brightness to maintain the desired level of illumination of the photo-sensitive surface or mosaic in the pick-up tube.

In the drawings:

Fig. 1 is a wiring diagram illustrating one way of practicing the invention.

Fig. 2 is a fragmentary front elevation of a portion of a television pick-up apparatus or camera illustrating portions of the invention.

Fig. 3 is a vertical cross-section taken on line 3—3 of Fig. 2.

2

Fig. 4 is a horizontal cross-section taken on line 4—4 of Fig. 3.

Fig. 5 is a detail cross-section taken on line 5—5 of Fig. 4.

The present invention may be used with any type of television pick-up tube, apparatus, or camera. It is customary to provide television cameras with a focusing lens and an iris adjustable for changing the size of opening for the path of light focused by the lens on the photo-sensitive surface or mosaic of a television tube. It is usually desirable to adjust the iris so that the opening through the iris will provide for the passage of the desired amount of light to obtain an illumination of the photo-sensitive surface or mosaic in the tube that will provide the desired contrast in the picture. The present invention provides means for setting and automatically adjusting the iris to produce this result by using the video signal as a means for adjusting the setting of the iris as scene illumination increases or decreases. It also provides for using a photo-electric cell as a means for controlling the iris instead of the video signal so that the invention may be applied to all types of cameras.

The invention may be applied to any suitable type of television camera or pick-up apparatus which will usually include a casing 1 as shown in Figs. 2 to 5 having a front wall 2, bottom wall 3 and side wall 4. The focusing lens is mounted in an aperture in the front wall and may include as a unit an adjustable iris or the iris may be a separate unit mounted on or adjacent the lens. The iris is indicated diagrammatically in the drawings at 5. The iris has an outside rotatable ring member that provides a means for adjusting the size of the iris aperture. For the purpose of the present invention this ring member is preferably provided with a peripheral groove to receive an endless belt 6 operable for adjusting the iris. Belt 6 is engaged over pulley 7 mounted on shaft section 8 rotatable in bearing bracket 9 pivotally mounted at 10 on front wall 1. A tension spring 11 normally operates bearing bracket 9 so as to move it about pivot 10 and maintain belt 6 under tension for effectively rotating the ring of iris 5 in the rotation of pulley 7 to adjust the size of the iris opening. Tension spring 11 has one end secured to bearing bracket 9 and the opposite end to the front wall 2 of casing 1. A suitable shaft coupling 12 connects the free end of shaft 8 with one end of shaft section 13 having the other end connected by means of a universal joint 14 to the end of shaft 15 of limit switch unit 16, shown in Figs. 3 and 4.

Limit switch unit 16 has a U-shaped supporting bracket 17. The bottom portion of bracket 17 is secured to side wall 4. Shaft 15 is rotatably mounted in bearing 22 carried by one leg of bracket 17 in transversely extending relation while the other leg mounts a gear reduction unit 18 having a shaft projecting through the adjacent leg of bracket 17 and intercoupled with the free end of shaft 15, as indicated at 19 in Fig. 4. A reversible electric motor 20 is mounted on gear reduction unit 18 while suitable spacing sleeves and screws indicated at 21 are secured to one wall of casing 1 and gear reduction unit 18 for cooperation with the leg of bracket 17 for rigidly supporting the motor and gear reduction motor in the casing.

A pair of snap switches known as microswitches are mounted between the legs on bracket 17 at one side of shaft 15, as shown in Figs. 3 and 4 and indicated at 23. These snap or microswitches are used in a manner hereinafter described for limiting the rotation of shaft 15 through controlling the circuit to motor 20 for limiting the adjustment of the iris to predetermined open and closed positions.

The usual form of snap or microswitch constructed in a manner well-known in the art, is used for the limit switches 23. The operating pins of these switches have a resilient strip member 23' engaged over the free end thereof, as shown in Fig. 5. One end of strip member 23' is mounted on the switch body while the free end is engaged over the switch operating pin, one strip being provided on each microswitch 23. This provides a means that will efficiently cooperate with the switch operating fingers that will now be described.

A pair of collars 24 and 25 respectively, is secured on shaft 15 in desired positions of adjustment by means of suitable set screws, as shown in Figs. 4 and 5. Collar 24 has a switch-operating finger 26 projecting radially therefrom and arranged to engage resilient strip 23' of one of the microswitches 23, as shown in Fig. 4, for moving the operating pin to disengage the switch and the circuit controlled thereby for opening the circuit to motor 20 at one limit of adjustment of the iris. Collar 25 has a finger 27 formed with an offset end, as shown in Fig. 4, aligned for engagement with the strip 23' of the other microswitch so as to operate the switch and open the contacts therein for controlling the motor circuit at the opposite limit of adjustment of the iris. In order to effect this switch operation and control of motor 20 it will be noted that one of the microswitches is reversed in its position on bracket 17 with respect to the other switch. This provides for fingers 26 and 27 engaging strips 23' in advance of the operating pins in the direction in which they rotate in their switch operation so that strips 23' operate in conjunction with fingers 26 and 27 to cam one of the microswitches into open position.

The television pick-up tube is diagrammatically indicated in the drawings in all of the views and designated by numeral 30. The end of the tube provided with the usual photo-sensitive surface or mosaic, not shown, is directed toward and aligned with the lens for the camera and in rear of iris 5 in spaced relation as shown in Fig. 4, so that the lens can be adjusted to focus the image of a scene on the photo-sensitive surface or mosaic in a manner well-known in the art. The television pick-up tube 30, shown diagrammatically in the drawings, may be any suitable type

of television pick-up tube now well-known in the art, and will have the various apparatus for operating and controlling the operation of the tube provided in the usual manner. This apparatus will include the usual video amplifier 31 shown diagrammatically in Fig. 1.

The present invention uses the video signal as a means for adjusting the setting of the iris. The amplitude of the video signal is in general proportional to scene brightness, other things being substantially equal. Under these conditions an increase in scene brightness will cause an increase in video signal amplitude and a decrease in scene brightness will cause a decrease in video signal amplitude. It is this variation in video signal amplitude that is used to secure the adjustment of the iris for the purpose of maintaining substantially uniform illumination of the photo-sensitive surface or mosaic in the pick-up tube during substantially wide changes in scene brightness.

The invention provides a circuit arrangement for obtaining the control and adjustment of the iris automatically, and for this purpose, a circuit is made through wire 32 connected to the grid of the last stage of video amplifier 31 through isolating resistance 33 to grid 34 of amplifier tube 35. Grid 34 has a suitable negative bias applied through circuit wire 36 including isolating resistor 37. Wire 36 is connected to a bias battery or other source of voltage supply 38 having the opposite terminal grounded.

Amplifier tube 35 has a cathode 39 and an anode 40. Cathode 39 is connected to ground by wire 41. Anode 40 of amplifier 35 has a wire 42 connecting it to load resistor 43 in turn connected through wire 44 to the positive terminal of battery 45. The negative terminal of battery 45 is grounded through wire 46 completing the circuit of the amplifier portion of tube 35 through plate 40 and cathode 39.

The alternating component of the plate voltage in the circuit including anode 40 is applied through condenser 47 to cathode 48 of the rectifier portion of tube 35. A load resistor 49 is connected to cathode 48 at one end and is grounded at the other end as indicated at 50. A positive bias voltage is applied to anode 51 through wire 52 connected to resistor 53 which is connected in turn to an adjustable voltage divider 54. One end of divider 54 is grounded at 55 and the opposite terminal of divider 54 is connected to wire 44 to complete the voltage divider circuit and the rectifier circuit to cathode 48 through ground 50. Resistor 53 is the load resistor for the rectifier portion of tube 35. The rectified current through the circuit including cathode 48, anode 51 and resistor 53 develops a varying direct current voltage across the terminals of resistor 53.

The varying direct current voltage in the rectifier portion of tube 35 is filtered in the resistance-capacity filter network indicated at 56. The operating characteristics of this automatic iris control are governed to a substantial extent by the design of the filter 56 through the selection of suitable values for the resistances and condensers used in this filter so that the time constant for desired conditions of operation may be obtained. Filter 56 has an input terminal 57 connected to wire 52 on the anode side of resistor 53. The output terminal 58 of the filter is connected through resistor 59 to grid 60 of amplifier tube 61. Resistor 59 is used to suppress parasitic oscillations. The rectified voltage from the rectifier portion of tube 35 applied to the filter input

57, is negative, and therefore applies a negative voltage to grid 60, negative with respect to cathode 62 of tube 61.

Amplifier tube 61 is shown in Fig. 1 diagrammatically as a pentode. The difference in voltage between the negative voltage developed by rectified current flowing in resistor 53 and the positive voltage obtained by voltage divider 54 is applied to input 57 of filter 56 and to grid 60. By varying the adjustment of resistor 54 the positive voltage can be varied to control the amplitude of the direct current voltage applied to grid 60. This provides a means of adjusting the iris to meet desired conditions of operation. The screen grid 63 is connected to battery 45 for applying a suitable voltage to establish a desired operating condition of a well-known character used in the operation of pentodes. The suppressor grid 64 is connected to cathode 62 in the usual manner. Cathode 62 is grounded as illustrated in Fig. 1.

Anode 65 of amplifier pentode 61 is connected by wire 66 through load resistor 67 to wire 44 for applying the positive voltage from battery 45 to anode 65 while the circuit with cathode 62 is completed through ground connection 46.

The setting of resistor 54 in the control of the grid 60-cathode 62 circuit of tube 61 provides the control means for determining the setting of the iris to obtain the desired intensity of illumination of the photo-sensitive surface or mosaic in television pick-up tube 30. In addition to setting the position of the iris, this grid 60-cathode 62 circuit of tube 61 is controlled by variations in amplitude of the video signal through the circuits in the amplifier-rectifier tube 35 through variation of the amplitude of the D. C. voltage applied to grid 60 obtained by the variation in amplitude in the circuit including anode 51 of tube 35. This provides the control for the iris to adjust the setting of the iris to either open or close the opening in the iris in the adjustment thereof for maintaining substantially uniform illumination of the photo-sensitive surface or mosaic in tube 30 during variations in scene brightness from that for which the iris is primarily set by the adjustment of resistor 54.

This control for the iris operates through a balanced system for controlling operation of the iris setting means or mechanism.

The means for governing the operation of reversible motor 20 employs a tube 68 which may preferably be in the form of a double triode, that is one having two triode sections. One triode section has cathode 69, grid 70 and anode 71 while the other section has cathode 72, grid 73 and anode 74.

A wire 75 connected to wire 66, as shown in Fig. 1, connects anode 65 with grid 70 and wire 76 connected to wire 66 also connects anode 65 to cathode 72, so that all three elements operate at the same direct current potential. A voltage-dividing network consisting of resistors 77, 78, 79, 80 and 81 has one end of the network connected to wire 44 for placing it in circuit with the positive terminal of battery 45 and the other end of the network connected to ground at 82 for completing the circuit of the network with the negative terminal of battery 45 through ground connection 46. This voltage dividing network is used to provide the desired potential, positive with respect to ground, for the operation of the circuits connected with the double triode 68. Cathode 69 of tube 68 is connected by wire 83 to the junction of resistors 77, 78 and 80, so that

cathode 69 is at a higher positive potential than grid 70. Grid 73 is connected to the junction of resistors 78 and 79 by wire 84 at a point of lower positive potential than cathode 72. The values of resistors 77, 78, 79, 80 and 81 are selected so that the potentials of the points to which wires 83 and 84 are connected are such that grids 70 and 73 are negatively biased with respect to cathodes 69 and 72, respectively, in such amount that under resting conditions, that is when there is no change in amplitude of the video signal, the plate current is substantially zero in each triode section of tube 68.

Anode 71 of tube 68 is connected through wire 85 to solenoid winding 86 of relay 87. The other terminal of the winding 86 of the solenoid is connected through wire 88 to switch blade 128 and contact 89 of switch 90. Contact 89 is connected through wire 91 to wire 44 and the positive terminal of battery 45. The anode circuit is completed through wires 91, 44, resistor 77 and wire 83 to cathode 69.

Anode 74 of tube 70 is connected through wire 92 to one end of solenoid winding 93 of relay 94. The other terminal of solenoid winding 93 is connected through wire 98 to switch blade 128 to contact 89 of switch 90 and then through wire 91 to the positive terminal of battery 45. The anode circuit is completed through wire 44 and resistor 67 to cathode 72.

Relays 87 and 94 are of the single-pole double-throw type. The back contact 95 of relay 87 and back contact 96 of relay 94 are connected together and to the positive terminal of battery 97 through wire 98. The other terminal of battery 97 is connected to ground as indicated at 99. When solenoid windings 86 and 93 are not energized, armature 100 of relay 94 connects contact 96 through wire 102 to switch blade 103 of switch 90 and armature 101 of relay 87 connects contact 95 through wire 102 to switch blade 103 of switch 90.

Contact 104 of relay 94 is connected to switch 105, a normally closed switch of the spring action type generally known in the art as a microswitch. The switch 105 indicated in Fig. 1 is comprised of one of the switches 23 shown in Figs. 2 and 3 and is one of the limit switches. Limit switch 105, inductor 106 and field coil 107 of motor 20 are connected in series. The other terminal of field coil 107 is connected to armature 108 of motor 20 as indicated at 109. The remaining terminal of armature 108 is connected to ground 110, thus completing the motor circuit through battery 97 when armature 100 makes contact with contact 104 of relay 94.

Switch 113 in Fig. 1 is the other limit switch 23 shown in Figs. 3 and 4 and is connected in series with contact 112 of relay 87, inductor 114 and field coil 115 of motor 20. The other terminal of field coil 115 is connected to motor armature 108 at 109. When relay armature 101 makes contact with contact 112, motor field 115 and armature 108 are energized by battery 97. Field coils 107 and 115 of motor 20 are oppositely wound so that the direction of rotation of armature 108 is dependent upon the selection of the desired field coil. Condenser 116 is connected between the grounded terminal of armature 108 of motor 20 and the junction of field coil 107 and inductor 106. Condenser 118 is connected between the grounded terminal of armature 108 and the junction of field coil 115 and inductor 114. Condensers 116 and 118 in conjunction with inductors 106 and 114 suppress electrical disturbances arising

ing from sparking at the commutator brushes of armature 103 in a manner well-known in the art. Condenser 119 connected between connection 109 and a ground at 120, and resistor 121 connected between connection 109 and ground 122 provide additional suppression of disturbances arising from sparking at the commutator brushes. Limit switches 105 and 113 are operated by fingers 26 and 27 on shaft 15 during adjustment of the iris in such a way that when the lens iris has been closed to a selected limiting value by motor 20 switch 113 is opened by the finger 26 for example, thus disconnecting motor 20 from battery 97. When the lens iris has been opened by operation of motor 20 to a selected limiting value, switch 105 is opened for example, by finger 27, disconnecting motor 20 from battery 97.

Resistor 123 is connected to armature 100 of relay 94 through wire 102. Resistor 124 is connected to armature 101 of relay 87 through wire 102. The opposite terminal of resistor 123 is connected through wire 125 to contact 104 while the other terminal of resistor 124 is connected through wire 126 to contact 112. Resistors 123 and 124 are connected across the relay contacts of relays 87 and 94 to suppress sparking at the relay contacts on making and breaking the circuit. A condenser 127 is connected to contacts 95 and 96 through wire 98 and the opposite terminal of the condenser is grounded at 129. Condenser 127 cooperates in the suppression of the sparking or arcing at the relay contacts.

Switch 90 provides a means for changing from manual to automatic control of the adjustment for the lens iris. Switch 90 is of the double-pole double-throw type, with blades 103 and 128 acting together. With switch 90 in a position where blade 128 makes contact with contact 89, relays 87 and 94 and anodes 71 and 74 of tube 68 are connected to battery 45 so that tubes 68 receive power so that the circuit through anodes 71 and 74 are energized. Blade 103 of switch 90 makes contact with switch terminal 130 having no circuit connection.

When switch 90 is in such a position that blade 103 makes contact with contact 131, wire 102 is connected to switch blade 132 of the switch indicated at 133. Simultaneously switch blade 128 of switch 90 is in contact with contact 134 disconnecting the circuit through wires 88 and 91 and battery 45. relays 87 and 94 together with anodes 71 and 74 of tube 68 so that tube 68 and the circuits associated therewith for controlling motor 20 will be deenergized.

With contact 131 and armature 103 of switch 90 in contact, power from battery 97 may be applied to motor 20 through wire 135 to field coil 115 by setting switch 133 so that switch blade 132 makes contact with contact 137. The power may be applied to operate motor 20 through field coil 107 by moving switch blade 132 of switch 133 to engage contact 136 to complete the circuit through wire 125 to contact 104. Manual operation of switch 133 may therefore be used when switch 90 is operated to the manual control position for securing adjustment of the iris to or toward either open or closed positions. This manual adjustment of the iris is obtained independently of the automatic setting and control thereof.

In operation, the iris first is set to the desired position through adjustment of variable resistor 54. Then in the subsequent operation of the television pick-up apparatus, the amplitude of the video signal which is in general proportional to

scene brightness, other things being equal, will serve to control and produce automatic adjustments of the iris with changes in amplitude of the video signal caused by changes in scene brightness. As above pointed out, an increase in scene brightness will normally cause an increase in video signal and a decrease in scene brightness will cause a decrease in video signal.

If the scene brightness increases, the resulting increase in video signal will cause the negative direct current voltage at grid 60 of tube 61 to increase. This in turn causes the anode current of tube 61 to decrease, with the result that the voltage drop across resistor 67 also decreases since this resistor is part of the anode circuit of tube 61. Since the direct current voltage between grid 70 and cathode 69 of tube 68 is equal to the difference between the positive (with respect to cathode 69) voltage drop across resistor 77 and the negative voltage drop across resistor 67, a decrease in voltage drop across resistor 67 will cause the voltage at grid 70 to become more positive with respect to cathode 69. Consequently the current in the circuit including anode 71 and cathode 69 will increase. When the increment in current to anode 71 becomes sufficiently large, relay 87 will operate by solenoid winding 89 being energized to move armature 101 into engagement with contact 112 for closing the circuit through field coil 115. This energizes electric motor 20 to operate in one direction to adjust the iris toward closed position through the rotation of pulley 7 by the shaft connection thereof with the motor and the adjustment of the iris through movement of belt 6. As the lens iris closes, the intensity of illumination on the photo-sensitive mosaic of the television pick-up tube 30 decreases, thereby decreasing the amplitude of the video signal. Thus the negative direct current voltage at grid 60 of tube 61 decreases, the anode current in the circuit including anode 65 of tube 61 increases, the voltage drop across resistor 67 increases, grid 70 of tube 68 becomes less positive with respect to cathode 69, and the current in the circuit including anode 71, cathode 69 and solenoid winding 89 decreases. This process continues until the current decreases to a value which deenergizes relay 87 to open the circuit at armature 101 and contact 112 thus disconnecting motor 20 from the source of electrical energy 97. When this occurs motor 20 ceases rotation and the lens iris remains in adjusted position. Since the initial balance of the system was based on a video signal of selected value, as determined by the setting of variable resistor 54, the new setting of the iris will be one in which the illumination of the mosaic in the pick-up tube will have a value that will result in a video signal of the initial value. The control therefore automatically maintains constant video signal output under increasing scene brightness within the limits of adjustment of the iris for changing the size of the aperture therein by reducing it to a minimum size.

When scene illumination decreases the resulting decreased video signal will cause the negative direct current voltage at grid 60 of tube 61 to decrease, thereby increasing the current in the circuit including anode 65 of tube 61. Thus the voltage drop across resistor 67 increases. The direct current voltage between grid 73 and cathode 72 of tube 68 is equal to the algebraic sum of the voltage drop across resistor 78 (negative

with respect to cathode 72), resistor 77 (negative with respect to cathode 72), and resistor 67 (positive with respect to cathode 72). Therefore when the voltage drop across resistor 67 increases, grid 73 becomes more positive with respect to cathode 72, causing an increase in the current flowing in the circuit including anode 74, cathode 72, and solenoid winding 93 of relay 94. When the increment of current in this circuit becomes sufficiently large, relay 94 will operate, operating armature 100 to engage contact 104 thereby closing the circuit through field coil 101 of motor 20 for securing operation of the motor. The motor will operate to open the iris by means of the rotation of shaft 8, pulley 7 and operation of belt 6. As the iris opens the illumination on the pick-up tube mosaic increases, causing an increase in the video signal. As a result, the negative direct current voltage at grid 60 of tube 61 increases, the anode current of tube 61 through anode 65 decreases, the voltage drop across resistor 67 decreases, the direct current voltage at grid 73 becomes more negative and the current in the circuit including anode 74, cathode 72 and relay solenoid winding 93 decreases. As the motor continues to open the iris this process continues until the current through relay solenoid winding 93 decreases to a value that causes the relay to open, breaking the motor circuit between armature 100 and contact 104 when motor rotation will cease and the iris will remain in adjusted position. At this point the video signal amplitude is that determined by the initial setting of variable resistor 54 thereby obtaining automatic control of the iris for maintaining constant video signal output under conditions of decreasing scene brightness within the limit of the maximum degree of opening of the iris.

It will therefore be understood that the opening in the iris may be initially set by adjustment of variable resistor 54 for a desired intensity of illumination of the mosaic in tube 39 for a given scene brightness and that when scene brightness varies thereafter in the operation of the television pick-up apparatus, the variation in scene brightness causing a change in amplitude of the video signal will secure operation of the motor 20 to automatically adjust the iris toward either open or closed positions to maintain substantially uniform illumination of the mosaic in the pick-up tube.

The circuit connected with tube 68 provides a pair of independent but intercoupled operating circuits or operating means for securing operation of motor 20 through the cooperation of relays 87 and 94. The anode circuit of anode 65 of tube 61 being intercoupled with both triode sections of tube 68 is arranged to control the balance between the two operating circuits for the relays 87 and 94 for securing and maintaining the initial adjustment of the iris in accordance with the setting of variable resistor 54 and in addition provides a control means for securing operation to adjust the iris through the variations in amplitude of the video signal being transmitted and impressed upon the circuit including anode 65 hereinabove described to secure operation of motor 20 for adjusting the iris to both increase and decrease the size of the lens aperture. Tube 39 with its amplifier and rectifier portions operates through the rectifier portion including the circuit with anode 51 to provide a control means for controlling iris adjustment for obtaining the desired lighting of the mosaic in the pick-up tube 30, and maintaining this illumination in a sub-

stantially constant manner through variations in scene brightness by using changes in amplitude of the video signal impressed upon the circuit including anode 51 for securing energization of one or the other of the two motor operating circuits and relays 87 and 94 to operate the motor and adjust the iris.

The battery symbol used in the wiring diagram, Fig. 1, is for convenience in illustration and it is to be understood that other conventional sources of electrical energy other than batteries may be used in a manner now well-known in the art and are contemplated by the invention disclosed herein.

15 A photo-electric cell may be used to automatically operate the iris to adjust the size of the lens aperture by connecting the output of such a cell to grid 34 or grid 60 and using the remainder of the wiring connections and apparatus as shown in Fig. 1 and described above.

20 The word "iris" as used in the foregoing description and in the claims shall be interpreted to define a device for controlling the size of aperture for light passage through a lens of an optical system that may be operated to vary the size of said aperture in any suitable manner for controlling the character of illumination of an image so that a uniform image illumination may be obtained with variations in scene brightness. The word "iris" shall be further interpreted to define any spatial electromagnetic wave attenuating device such as a light filter or plurality of light filters interposed in the transmission path of such wave.

25 30 The word "light" as used in the foregoing description and in the claims shall be interpreted to define electromagnetic waves in both the visible and invisible portions of the electromagnetic wave spectrum, including ultra-violet and infrared waves.

35 40 It is to be further understood that the motor hereinabove described may drive any type of control device such as a rheostat connected in circuit with the light source to control the light source for obtaining uniform illumination rather than to control the light reaching the brightness variation sensitive element. Or the control voltage may be applied to the input circuit of one or more electron tubes, known as Thyratron tubes, to control the power applied to electric lamps connected to the output circuit of said electron tubes. In fact, the operating means herein described may be used to operate many different types of variable controlling apparatus where it is desired to introduce an automatic control of apparatus that varies in operation so as to maintain a substantially uniform condition of operation of such apparatus. The invention uses a potential variable with the variation in operation of the means to be controlled and with the initial control setting means obtains an automatic control of the operation to obtain a substantially uniform and desired condition of operation.

45 50 The invention claimed is:

55 60 65 70 75 1. In a television pick-up apparatus having a pick-up tube, a video amplifier and an adjustable iris for controlling the light intensity focused on the mosaic of said pick-up tube, the combination of a reversible electric motor connected to adjust said iris to enlarge and reduce the size of the opening therein in rotation thereof in opposite directions, a pair of electro-magnetic operated means each controlling operation of said motor in one direction, a double triode having a pair of normally balanced circuits coupled therewith each controlling one of said electro-magnetic op-

erated means, and circuit means responsive to variations in amplitude of the video signal coupled with said double triode for unbalancing one of said pair of circuits to secure motor operation for adjusting said iris to maintain a substantially uniform video signal amplitude during variations in scene brightness.

2. In a television pick-up apparatus having a pick-up tube, a video amplifier and an adjustable iris for controlling the light intensity focused on the mosaic of said pick-up tube, the combination of electrically actuated iris setting means, an electronic control system having a pair of input and output circuits, each output circuit coupled to electrically operate said setting means in one direction for operating said iris to either open or close the lens aperture, said input circuits being coupled to control both output circuits, one input circuit having means coupled therein to secure operation at a constant potential, an amplifier having an output circuit coupled with the other of said input circuits for varying the potential thereof relative to the potential of said first-mentioned of said input circuits, said amplifier having an input circuit including means adjust-

able for setting the voltage amplitude therein and setting the iris for a desired illumination of the mosaic, and an electronic operated means responsive to variations in video amplitude for impressing said variations on said amplifier input circuit for varying the voltage amplitude therein whereby said iris will be adjusted in response to variations in amplitude in the video signal for maintaining a substantially uniform video signal during variations in scene brightness.
